CYLINDER SLEEVE PRESS

Frank S. Heimbach and William Leischel,
Chicago, Ill.

Application June 3, 1935, Serial No. 24,782

7 Claims. (Cl. 29—88.2)

This invention relates to improvements in cylinder sleeve presses for pressing replacement sleeves into cylinder blocks. When a cylinder has cracked or become deeply scored it is remedied and made as good as new by pressing thereinto a sleeve, the cylinder having been bored $\frac{1}{4}$ " to receive the same. It is the purpose of the present invention to provide means for readily inserting such sleeve.

10 One object is to provide a sleeve press that is readily portable and that may be applied to the cylinder block without the use of tools of any kind. A further object is to provide a press that is very compact in assembly in order that it may 15 be applied as readily to the last cylinder, or the one farthest from the radiator, as to any other cylinder of the block.

A further object is to provide a press that may be applied to the block without danger of breaking the same. In the present press the pressure applied to the top of the sleeve is exerted between 20 two resistance points, one above the pressure point and the other resistance point disposed below the pressure point at the bottom or base of 25 the cylinder, both resistance points and the pressure point falling wholly within the plane of the sleeve or of the cylinder. In this assembly there is no lateral pull upon the cylinder block and breakage of the same is not possible.

30 With the foregoing and other objects in view the invention consists in the combination and arrangement of parts to be hereinafter fully described, pointed out in the claims and illustrated in the accompanying drawings which form a part 35 of this application for patent and in which—

Fig. 1 is a perspective view of the sleeve press showing its application to a cylinder block.

Fig. 2 is a longitudinal sectional view through Fig. 1.

40 Fig. 3 is an end view of Fig. 4.

Fig. 4 is a view in elevation of a replacement sleeve.

Fig. 5 is a view of the anchor washer employed.

45 Fig. 6 is an edge view of Fig. 5.

Fig. 7 is a top plan view of Fig. 1.

Fig. 8 is a cross sectional view through Fig. 2 on the line 8—8.

Like reference characters denote corresponding parts throughout the several views.

50 The reference numeral 1 denotes a cylinder block having the cylinders 2, and 3 is a replacement sleeve adapted for application to the cylinders. The press includes a stationary frame having the opposed spaced sides 4, 5 of channel

6 and by the plate 7 which is secured to the transverse angles 8 connected by bolts 9 to the frame sides. The frame 4, 5 is adapted to stand upon one end resting upon the cylinder block about the cylinder under operation. The frame sides are formed with perforations 10 adapted to receive the removable stop pins 11 for the floating stop plate 12 that freely connects the sides of the stationary frame.

Arranged within the stationary frame is the traveling frame comprising the head plate 13 and base plate 14 connected together by the spacer rods 15 that extend through perforations in the plate 7 and have their ends reduced for positive engagement with perforated portions in said plates 13, 14. The latter plates are shaped for close fitting sliding engagement with the sides 4, 5 of the stationary frame. The base plate 14 is adapted to rest upon the upper end of the replacement sleeve 3 to directly force the same into the cylinder.

The plate 14 is formed with a central perforation 16 that is in line with and of the same diameter as a similar perforation in the plate 7 to receive a guide bolt 17, threaded at its ends, that passes entirely and centrally through the replacement sleeve and through the cylinder and to the lower end of which outside the bottom of the cylinder the washer 18 is applied that abuts the base of the cylinder block at the lower end of the cylinder, a nut 19 threaded upon the bolt 17 retaining said washer in position. A nut 20 at the upper end of the bolt 17 resting upon the plate 7 holds said members together. An hydraulic ram or an ordinary automobile jack or like tool (not shown) is placed upon the head plate 13 with its plunger engaging the stop plate or resistance plate 12. This jack or tool is placed centrally of the plate 13 so that it is in line with the bolt 17. When the jack, or ram, is manually operated it will force the travelling frame downward within the stationary frame thus pressing the sleeve 3 into the cylinder. The points of resistance, which are the nuts 19 and 20 and that portion of the plate 12 engaged by the ram or jack, and the point of pressure exerted by the ram or jack upon the plate 13 all fall within and centrally of the sleeve and cylinder so that no side pressure is set up outside the press which greatly reduces the strain upon the cylinder block and prevents otherwise possible breakage of the same.

The bolt 17 centers the travelling frame with respect to the stationary frame. In operation the jack or ram supports the floating stop plate 12 while the stop pins 11 prevent its riding up-

ward above said pins. As the sleeve is forced into the cylinder the jack or ram becomes extended to its limit and at such time the plate 12 and pins 11 are moved down to permit disposal 5 of the pins into the lower set of perforations 10 when the operation is repeated until the sleeve is forced completely into the cylinder. In applying the press to the cylinder block it is merely set upon the same about the cylinder under operation and the bolt 17 and anchor means 18, 19 10 will positively hold it in this position while the operation is being performed. Nor is it necessary that the washer 18 be tightened firmly against the base of the cylinder block. It need only be disposed thereagainst and so retained by the nut. 15

What is claimed is:

1. In cylinder sleeve presses, a stationary frame for disposal upon the cylinder block, means passing through the sleeve and cylinder and releasably secured to the lower end of the latter and to the frame whereby said frame is secured in position, a travelling frame within said stationary frame and centered with respect thereto and to the cylinder, a ram carried by said travelling frame, and adjustable resistance means for said ram carried by said stationary frame. 20

2. In cylinder sleeve presses, a stationary frame, means for connecting said frame and the cylinder together concentrically, a travelling frame within said stationary frame and concentric therewith, a ram carried by said travelling frame, and resistance means for said ram carried by said stationary frame. 25

3. In cylinder sleeve presses, a stationary frame, a travelling frame concentric therewith for engagement with the sleeve, a ram carried by said travelling frame, resisting means for said ram carried by said stationary frame, and a guide bolt connecting said travelling frame and the lower end of the cylinder and passing through the sleeve whereby said members are retained in concentric relation. 35

4. In cylinder sleeve presses, a stationary

frame, a floating stop plate therewithin, stop pins therefor, a travelling frame within and concentric with said stationary frame, said travelling frame being adapted to engage one end of the sleeve, a guide bolt engaging said travelling frame and extending centrally through the sleeve and cylinder, means for securing said bolt to one end of the cylinder at the base of the block, and a ram carried by said travelling frame for engagement with said stop plate. 5

5. In cylinder sleeve press mechanism, an anchor at the base of the cylinder block in line with a cylinder, a stationary frame, a floating stop plate above the cylinder block within said stationary frame, stop pins for said stop plate 10 removably carried by said stationary frame, a guide bolt connecting said stationary frame and anchor and passing centrally and longitudinally through the sleeve and cylinder, a travelling frame carried by said stationary frame and movable over said guide bolt, and a ram carried by said travelling frame for engagement with said stop plate. 15

6. In cylinder sleeve presses, a stationary frame having spaced channel sides, brace connections between said sides, a travelling frame arranged in said stationary frame and including spacer rods passing through one brace connection, a bolt engaging said travelling frame and passing through the sleeve and cylinder, a washer at one end of said bolt abutting the base of the cylinder, a nut carried by said bolt engaging said washer, a ram carried by said travelling frame, and adjustable stop means for said ram carried by said stationary frame. 25 30

7. In cylinder sleeve presses, anchor means at the base of the cylinder block, a stationary frame, means for connecting said frame and anchor means together, and sleeve actuating means at the head of the cylinder block for pressing the 40 sleeve into the cylinder. 35
